SHIRT

Robert D. Gwynn, Detroit, Mich.

Application June 16, 1949, Serial No. 3,333

Term of patent 3½ years

(CL. D3—25)

To all whom it may concern:

Be it known that I, Robert D. Gwynn, a citizen of the United States, residing at Detroit, in the county of Wayne and State of Michigan, have invented a new, original, and ornamental Design for a Shirt, of which the following is a specification, reference being made to the accompanying drawing, forming part thereof.

Fig. 1 is a front elevational view of a shirt showing my new design; and

Fig. 2 is a rear elevational view thereof.

I claim:

The ornamental design for a shirt, as shown.

ROBERT D. GWYNN.
